UNITED STATES PATENT OFFICE.

JOSEPH F. BUTLER, OF PITTSBURGH, PENNSYLVANIA.

MACHINE-GUN MOUNT.

Application filed February 25, 1927. Serial No. 170,960.

This invention relates to mounts for machine guns, the general object of the invention being to provide a mount having a number of machine guns movably supported thereon, with means for simultaneously shifting the muzzles of the guns so that their bullets will spray all parts of a certain area, the center of which is covered by the sights of the mount so that a target in this area cannot escape being struck.

Another object of the invention is to provide a bar which supports the muzzles of the guns and which is supported for rocking and sliding movement on the mount, with eccentric means connected with one end of the bar for moving the same.

A still further object of the invention is to provide means for adjusting the eccentric so that the bar can be given different degrees of movement.

Another object of the invention is to provide a motor for driving the eccentric means and to so form the adjustable means that adjustments can be made while the motor is in operation.

Another object of the invention is to provide means for raising and lowering one end of some of the guns.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is an elevation showing the improved mount in use.

Figure 2 is a plan view of the mount.

Figure 3 is a rear end view thereof.

Figure 4 is a front end view thereof.

Figure 5 is a section on line 5—5 of Figure 3.

Figure 6 is a section on line 6—6 of Figure 5.

Figure 7 is a section on line 7—7 of Figure 5.

Figure 8 is a section on line 8—8 of Figure 2.

Figure 9 is a section on line 9—9 of Figure 2.

Figure 10 is a section on line 10—10 of Figure 2.

Figure 11 is a section on line 11—11 of Figure 2.

Figure 12 is a section on line 12—12 of Figure 11.

Figure 13 is a section on line 13—13 of Figure 2.

Figure 14 is a section on line 14—14 of Figure 13.

Figure 15 is a fragmentary view of a supporting bar having the forked end for engaging the eccentric pin.

Figure 16 is a fragmentary view of another supporting bar, the pin engaging slot in which is vertically arranged.

In these views, the mount is shown at 1 and is in the form of a flat frame or platform having the depending flanges 2 which carry the trunnions 3 which are journaled in the upright 4 of the supporting frame A which may be fastened to a rotatable platform when the device is used as an anti-aircraft gun. The toothed segment 5 is fastened to one of these flanges and engages the worm 6 on the shaft 7 which is adapted to be rotated by the hand wheel 8. This will enable the mount to be rocked to train the guns on a target. This arrangement of supporting means for the mount is optional, as any suitable supporting means can be used with the improved mount.

A bar 9 is supported at the front of the frame or platform by means of a roller 10 which has its horizontal pintles 11 journaled in a bracket 12 fastened to the platform and this roller has a hole 13 therein for slidably receiving the bar. One end of the bar has a bearing 14 thereon which receives an eccentric pin 15 projecting from one end of the shaft 16 which is rotatably mounted in an eccentric bore 17 formed in a drum 18 which is rotatably mounted in the bearings 19 arranged at one end of the frame or mount. This drum has a ring gear 20 thereon which is engaged by a pinion 21 of a shaft of a motor 22 supported by the mount, so that the drum is driven by the motor. A second shaft 23 is mounted in the bore 17 and telescopes the inner end of the shaft 16, the two shafts being keyed together, as shown at 24. A spiral groove 25 is formed in the shaft 23 and is engaged by a pin 26 carried by the drum. A knob 27 is threaded in an opening formed in a support 28 110

fastened to the frame or mount and the inner end of the knob is formed with an annular interior groove 29 which receives a collar or flange 30 on the end of the shaft 23 so that as the knob is turned, it will be moved longitudinally in the threaded hole in the support 28 and thus the shaft 23 will be caused to move longitudinally with the knob and the groove 25 and pin 26 will 10 cause the shaft 23 to rotate as it is being moved longitudinally and thus the shaft 16 will be rotated to change the position of the eccentric pin 15. As will be seen, this pin can be moved to the center of the drum 15 where it will be in a neutral position and it will not move the bar 9, but when it has been moved out of this neutral position, the bar 9 will be rocked on its pivot formed by the roller 10 and it will be reciprocated longitudinally. It will also be seen that the pin can be adjusted through means of the knob 27 while the drum is in motion.

A pointer 31 is carried by the support 28 and cooperates with a scale or dial 32 on the 25 knob to indicate the amount of adjustment of the parts.

The machine guns are shown at B and these guns may be of any suitable type. The muzzles of the guns are held in supporting 30 members 33 which are fastened to the bar 9, the drawings showing two of the guns arranged at one side of the pivotal point 10 of the bar and another pair of guns are arranged on the other side of the pivotal point, 35 but it will, of course, be understood that any desired number of guns may be used. Anti-friction bearings 34 support the muzzles of the guns in the members 33 so that the muzzles can have free movement in the supporting 40 members.

One of these supporting members is hinged to the bar, as shown at 35, so that it can be rocked, and the means for so rocking the supporting member comprises a shaft 36 having one end journaled in a bracket 37 fastened to the mount adjacent the bar 9, with an arm 38 on the shaft which is connected with the free end of the hinged supporting member 33' by the link 39 so that when the 50 shaft is rocked, the support 33' will be moved on its hinge, as will be understood. Thus the muzzle of the gun can be raised from its neutral position with respect to the bar. While I have only shown one of these muzzle supporting members hinged, it will, of course, be understood that others of the guns can be so supported.

The means for rocking the shaft 36 comprises a shaft 40 carried by the rear of the 60 mount and having a worm 41 thereon which engages a worm gear 42 on the rear end of the shaft 36 so that by turning the crank handle 43 of the shaft 40, the shaft 36 will be rotated to raise or lower the supporting member 33'. The shaft 36 is formed in sec-

tions which are connected together by the flexible joints 36'.

In order to permit the muzzle ends of the guns to be adjusted, the rear ends of the guns must be movably supported. The guns on 70 the left hand side of Figure 2 are supported for this movement by being fastened to the bases 44, each base having a square stem 45 which ends in a spherical member 46, said member being held in a socket formed by an 75 upright 47 and its cap 48, the upright being fastened to the rear part of the mount or frame. An angle bracket 49 is pivotally secured to the top of the cap 48 and has a slot 50 therein which forms a guideway for the 80 square stem 45. This construction permits the rear end of the gun to move horizontally and vertically.

The guns on the right of Figure 2 have cylindrical heads 51 on their stems 45' and 85 these stems are rotatably mounted between the clamping jaws 52 rotatably mounted on a screw shaft 53 which is adjustable in a threaded socket in the upright 47', a handle 54 being connected with the upper end of the screw shaft to permit it to be adjusted. Thus these guns can also have their rear parts moved vertically and horizontally and these guns can also be raised and lowered 90 through means of the shaft 53.

A front sight 55 is supported by a V-shaped bracket 56 extending inwardly from the front bar of the frame or mount and a rear sight is arranged on the rear bar of the frame or mount and consists of a grooved 100 wheel 57 eccentrically mounted on a crank shaft 58 journaled in the uprights 59 so that by turning the crank handle, the grooved wheel forming the sight can be raised or lowered. These sights are in the same vertical 105 plane as the center of the fulcrum of the bar 9.

A searchlight 60 is adjustably mounted on one end of the frame.

As before described, the bar is given both a 110 reciprocatory movement and a rocking movement so that the muzzle ends of the guns are moved in a spiral but in some cases it may be desirable to simply move the muzzles of the guns in a vertical arc and when this is desired, a bar 9' is substituted for the bar 9 and this bar 9' has a forked end 9" for receiving the eccentric pin. This construction is 115 shown in Figure 15. Thus the bar is simply rocked on its fulcrum after being reciprocated.

I may also provide a bar 9* (Figure 16) to be substituted for the other bars, which is formed with a vertical slot 9* for receiving the eccentric pin so that this bar is simply reciprocated without being rocked.

From the foregoing it will be seen that with the sights trained on an object and with the eccentric means in operation, the guns will spray the bullets over the area,

the center of which is occupied by the object, and this area will be of considerable dimensions owing to the movements imparted to the muzzles of the guns by the eccentric pin. This area can be increased and diminished as the firing is taking place by turning the knob 27 to adjust the eccentric pin as it is being rotated by the drum. The area can also be increased by raising and lowering the gun or guns, which have their muzzle supports hinged to the bar. With the adjustable eccentric, the guns can be fired at a dead center by placing the pin in a neutral position so that the rotation of the drum will not change its position. Then by turning the knob, the pin can be moved from a neutral position so as to impart movement to the muzzles of the guns to scatter the shots and the radius of the spiral in which each muzzle is moving can be changed by turning the knob. Thus a target cannot get out of range without being struck after the sights have been trained on it. As before stated, by the use of a bar provided with a horizontal slot, the gun muzzles can be moved vertically, while with the use of a bar having a vertical slot, the muzzles of the guns can be moved in a horizontal plane. The sights are held on the target and then the guns are automatically moved to throw their bullets in a wide area to the target so that it is not necessary to sight the guns on a target. While this device is shown for use on an anti-aircraft gun, it will, of course, be understood that it can be used on aircraft and it can also be used in other situations.

The invention can also be used in units of one gun, one eccentric shaft, and one actuating bar with two or more units arranged on one mount and driven from the same motor.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A machine gun mount comprising a frame, a plurality of machine guns carried thereby, means for movably connecting the rear ends of the guns to the rear part of the frame, a movable member at the front of the frame, means for supporting the member so that it can have rocking and sliding movement, means for movably connecting the muzzle ends of the guns to said member and means for giving said member a combined sliding and rocking movement.

2. A machine gun mount comprising a frame, a plurality of machine guns carried thereby, means for movably connecting the rear ends of the guns to the rear part of

the frame, a movable member at the front of the frame, means for movably connecting the muzzle ends of the guns to said member, a drum carried by the frame, an eccentric pin carried by the drum and engaging the movable member to actuate the same, means for rotating the drum and means for adjusting the eccentric in relation to the drum.

3. A machine gun mount comprising a frame, a bar, means at the front of the frame for supporting the bar so that it will have sliding and rocking movement, a drum, an eccentric pin adjustably arranged on the end of the drum and engaging the bar for moving the same, means for rotating the drum, a number of machine guns, bearing members supported on the bar for receiving the muzzles of the guns and means at the rear of the frame for movably supporting the rear ends of the guns.

4. A machine gun mount comprising a frame, a bar, means at the front of the frame for supporting the bar so that it will have sliding and rocking movement, a drum, an eccentric pin adjustably arranged on the end of the drum and engaging the bar for moving the same, means for rotating the drum, a number of machine guns, bearing members supported on the bar for receiving the muzzles of the guns, means at the rear of the frame for movably supporting the rear ends of the guns, such means permitting the rear end of each gun to be moved vertically and horizontally.

5. A machine gun mount comprising a frame, a drum rotatably mounted thereon and having an eccentrically arranged bore, a shaft mounted to rotate in the bore, a pin eccentrically arranged on one end of the shaft and projecting from the end of the drum, manually operated means for rotating the shaft to adjust the pin in relation to the drum, means for rotating the drum, a bar mounted on the frame for sliding and rocking movement and having one end engaged by the pin, a plurality of machine guns, ball bearing means carried by the bar for receiving the muzzles of the guns and means for movably supporting the rear ends of the guns at the rear of the frame.

6. A machine gun mount comprising a frame, a drum rotatably mounted thereon and having an eccentrically arranged bore, a shaft mounted to rotate in the bore, a pin eccentrically arranged on one end of the shaft and projecting from the end of the drum, manually operated means for rotating the shaft to adjust the pin in relation to the drum, means for rotating the drum, a bar mounted on the frame for sliding and rocking movement and having one end engaged by the pin, a plurality of machine guns, ball bearing means carried by the bar for receiving the muzzles of the guns, one of such bearing means being hingedly connected

with the bar, means for moving the member on its hinge and means for movably supporting the rear ends of the guns at the rear of the frame.

5. 7. A machine gun mount comprising a frame, front and rear sights carried thereby and arranged at the center of the frame, a rotatable member at the front of the frame at the center thereof, said member having a slot therein, a bar passing through the slot, eccentric means at one end of the bar for actuating the same, bearing members on the bar for receiving the muzzles of machine guns and means at the rear end of the frame for supporting the rear ends of the guns.
10. 8. A machine gun mount comprising a frame, a drum rotatably mounted at one side thereof, an eccentric pin carried by the drum, a number of interchangeable bars adapted to be operated by the eccentric pin, one bar having a bearing at one end for engaging the pin, another bar having a longitudinal slot therein for engaging the pin and a third bar having a vertical slot at one end thereof for engaging the pin, means at the front of the frame in the center thereof forming a support for any one of the bars, means carried by the bars for supporting the muzzles of machine guns, means at the rear of the frame for movably supporting the rear ends of the machine guns and means for rotating the drums.
15. 9. A machine gun mount comprising a frame, a drum rotatably mounted at one side thereof, an eccentric pin carried by the drum, a number of interchangeable bars adapted to be operated by the eccentric pin, one bar having a bearing at one end for engaging the pin, another bar having a longitudinal slot therein for engaging the pin and a third bar having a vertical slot at one end thereof for engaging the pin, means at the front of the frame in the center thereof forming a support for any one of the bars, means carried by the bars for supporting the muzzles of machine guns, means at the rear of the frame for movably supporting the rear ends of the machine guns and means for rotating the drums.
20. 10. 11. In a device of the class described, a drum rotatably supported and having an eccentric bore, a shaft rotatably mounted in one end of the bore, an eccentric pin carried by the shaft, a second shaft rotatably mounted in the other end of the bore and telescoping with the first shaft, a key connecting the two shafts together, the second shaft having a spiral groove therein, a pin carried by the drum engaging the groove, a knob, means for causing longitudinal movement of the knob when the same is rotated, and means for movably connecting the knob with the second shaft so that the shaft will be moved with the knob.
25. 12. A machine gun mount comprising a frame, a bar, means at the front of the frame for supporting the bar so that it will have sliding and rocking movement, an eccentric device for moving the bar, means for operating the eccentric device, a gun, a bearing member for the muzzle of the gun supported on the bar, and means at the rear of the frame for movably supporting the rear end of the gun.

machine guns, means at the rear of the frame for movably supporting the rear ends of the machine guns, means for rotating the drums and means for adjusting the position of the pin on the end of the drum.

10. A machine gun mount comprising a frame, a plurality of machine guns carried thereby, a drum rotatably mounted on the frame, and having an eccentric bore therein, a shaft rotatably mounted in the bore, an eccentric pin on the shaft, means operated by the pin for moving simultaneously the muzzles of the guns, manually operated means for rotating the shaft to adjust the pin while the drum is moving and indicator means for indicating the extent of movement of the manually operated means.

11. In a device of the class described, a drum rotatably supported and having an eccentric bore, a shaft rotatably mounted in one end of the bore, an eccentric pin carried by the shaft, a second shaft rotatably mounted in the other end of the bore and telescoping with the first shaft, a key connecting the two shafts together, the second shaft having a spiral groove therein, a pin carried by the drum engaging the groove, a knob, means for causing longitudinal movement of the knob when the same is rotated, and means for movably connecting the knob with the second shaft so that the shaft will be moved with the knob.

12. A machine gun mount comprising a frame, a bar, means at the front of the frame for supporting the bar so that it will have sliding and rocking movement, an eccentric device for moving the bar, means for operating the eccentric device, a gun, a bearing member for the muzzle of the gun supported on the bar, and means at the rear of the frame for movably supporting the rear end of the gun.

In testimony whereof I affix my signature.

JOSEPH F. BUTLER.
